MARTIN RINEHART, OF LOCKPORT, ILLINOIS.

Letters Patent No. 84,441, dated November 24, 1868.

IMPROVED COMPOUND FOR TREATING PILES.

The Schedule referred to in these Letters Patent and making part of the same.

To all whom it may concern:

Be it known that I, MARTIN RINEHART, of the town of Lockport, in the county of Will, and State of Illinois, have invented certain new and useful Improvements in Compounding a Medicine, for the Curing of the Piles; and I do hereby declare that the following is a full, clear, and exact description thereof.

To enable others skilled in the art to construct and use my invention, I will proceed to describe it.

My invention relates to medical compounds, and consists of a new and useful composition of various substances possessing medicinal qualities, so as to form a salve for curing the distressing complaint popularly termed "the piles."

From my own personal experience, as well as from the experience of many others, I have found that this salve will effect a speedy and efficient cure.

I make my medical compound by taking three (3) grains of tannin-acid, two (2) grains of flowers of sul-

phur, one (1) grain of pulverized nutmeg, one (1) tablespoonful of lard, and one-half ($\frac{1}{2}$) tablespoonful of goose-oil, and mixing them thoroughly in a mortar until they form a salve.

These ingredients may be compounded in any other way suitable and convenient for the purpose, but I prefer the use of the mortar.

This salve I apply, in the usual way, to the parts diseased, with the most beneficial results.

Having thus described my invention,

What I claim, is—

The medical compound, consisting of the ingredients substantially as herein described, as a remedy for the piles, as set forth.

MARTIN RINEHART.
